UNITED STATES PATENT OFFICE.

PETER C. MOSSNER, OF SAGINAW, MICHIGAN.

FOLDING WASHBENCH.

Application filed November 5, 1920. Serial No. 422,108.

To all whom it may concern:

Be it known that I, PETER C. MOSSNER, a citizen of the United States, residing at Saginaw, in the county of Saginaw and State of Michigan, have invented certain new and useful Improvements in Folding Washbenches, of which the following is a specification, reference being had therein to the accompanying drawing.

10 This invention relates to improvements in folding wash benches, tables, and the like, and more especially to folding structures of this kind adapted to be attached to a support, a washing machine or other apparatus, 15 and to fold up in close relationship thereto.

The object of the invention is to provide an improved simple construction of this nature that when set up in operative position will afford a strong rigid support, and 20 that is capable of being readily folded into compact form in closely associated relation with the support.

A particular important novel characteristic of the invention resides in the provision 25 of improved means for bracing and locking the legs, said means being of simple construction capable of quick and easy operation, and of firmly holding the legs in extended position.

30 Another important novel feature of the invention lies in the provision, in combination with a washing machine having a swinging wringer, of a bench attachment adapted to fold against and within the confines of one side of the washing machine casing, said bench attachment having an extended supporting top part adapted to support a tub at the front side of the washing machine and also a tub off to one side thereof 35 in positions to cooperate with the wringer in different positions thereof in the performance of the several wringing and rinsing operations.

The invention, with other objects and advantages thereof, and the particular construction, combination, and arrangement of parts comprising the same, will be understood from the following detailed description, when considered in connection with 45 the accompanying drawings, forming part hereof, and illustrating one embodiment of the invention.

50 Figure 1 is a side elevation of a folding table structure constructed in accordance with the present invention and shown applied to one of the conventional types of

washing machines, the folding bench structure being shown in folded position.

Figure 2 is a top plan view, the bench structure being shown set up in operative 60 position.

Figure 3 is a perspective view of the bench structure in unfolded position.

Figures 4, 5, 6 and 7 are detailed views on an enlarged scale of the leg bracing and 65 locking means.

While a specific embodiment of the invention is illustrated in the drawings, it will of course be understood that minor changes and variations in the particular construction shown, the adaptation and use of the bench structure with machines other than washing machines, and the carrying out of the invention in other forms, as will appeal to those skilled in the art, and falling within the scope of the appended claims, may be practiced without departing from the spirit of the invention.

In the drawings, is shown one of the conventional forms of washing machines having 80 a rectangular shaped casing or frame 1 and equipped with a wringer 2 rotatably mounted upon a vertical shaft 3 and adapted to be adjusted and held in different positions by suitable locking means (not shown).

The particular construction of bench illustrated in the drawings, by way of example, comprises a top composed of two sections, 5, 6. The section 5 which is rectangular shaped, is shown made up of side 90 members 7, 8, 9 of angle iron suitably secured together, and intermediate metal slats 10 riveted, as shown, or otherwise suitably secured to the side bars 7, 8. The top section 5 at one side has a vertical hinge 95 connection with one side of the washing machine frame 1, the side bars 7, 8 at the inner side of said section being connected with hinge members 11 on the washing machine frame by pivot pins 13. The other 100 top section 6 is in the form of a frame composed of straight side bar portions 14, 15, a rounded end part 16 and cross slats 17, the sides and end parts 14, 15, 16 being shown constructed from a continuous angle strip 105 or bar. The top section 6 is hinged at one end to one side of the section 5 by pivots 18 engaging hinge members 19, 20 on the respective sections, and 21, 22 are supporting legs for the outer portions of the 110 respective sections, the parts being adapted to occupy the position indicated in Figs. 2 and

3 of the drawings with the section 5 located directly in front of the front side of the washing machine frame 1, and the section 6 extending laterally off to one side thereof, the respective sections 5, 6 extending at opposite sides of the pivotal axis of the wringer 2. The legs 21, 22 are pivotally connected to the top sections, 24 designating pivot bolts engaging brackets 25 on the sections 10 and suitable openings in the upper portions of the legs.

The legs 21, 22 are adapted to fold within the top sections 5, 6, and the top sections, which are near the same size and of a width 15 about equal the width of the front side of the washing machine frame 1 are adapted to be folded together flat against the side of the washing machine frame as indicated in Fig. 1 of the drawings, the top section 6 being 20 folded over laterally flat against the outer face of the top section 5, and the whole swung down against the side of the washing machine frame 1.

Means is provided for bracing and locking 25 the legs 21, 22 in unfolded position, that for each leg comprising an arm or rod 26 of spring metal, shaped as shown, and rigidly secured at one end portion 27 to one of the legs in any suitable way, for instance, as 30 shown, by rivets, the upper portion of the arm or rod 26 normally extending along the leg in spaced relation therewith. The upper end portion of the arm or rod is shaped as shown to provide a reduced part 28 with 35 shoulders 29, the reduced part 28 having an angularly disposed end portion 30. 31 designates a plate or strip rigidly secured to one of the top sections to extend adjacent the pivotal connection of the leg with said 40 section, the plate being provided with a notch 31'. When the leg is unfolded the spring arm or rod 26 moves outwardly, the upper reduced part 28 of the arm or rod springing into the notch 31' of the plate, 45 the angularly disposed end portion 30 and the shoulder portions 29 fitting respectively against the top and bottom faces of the plate 31, so that the leg is securely locked and braced in open position. The locking rods 50 or arms 26 are adapted to be operated to release the leg by pressing the same inwardly toward the leg.

It will be noted that the particular construction and arrangement of parts hereinbefore described provides a very simple folding bench structure that can be produced at small cost, that will afford a strong firm support and which can be easily set up and quickly folded in compact form. It will also 55 be observed that the special construction with a top section extending directly in front of the side of the washing machine and another section extending laterally beyond the same affords tub supports at each side of 60 the pivotal axis of the wringer, this arrange-

ment being of a very compact nature and providing for the convenient passing of the clothes from the washing machine through the wringer to the first tub from thence through the wringer to a tub on the other section, and from the latter through the wringer to a basket that can be positioned alongside of the washing machine, while at the same time the bench is adapted to fold flat against and within the confines of the front side of the washing machine. The special leg brace and lock is of a very simple nature, the particular interlock of the parts with the reduced part of the locking arm, and the shoulder portions and angular part fitting against the upper and lower faces of the notched part acting to securely brace and hold the leg firmly in its unfolded position.

What I claim is:—

1. In an apparatus of the class described, a support, a bench comprising a top section having a hinge connection at one side to one side of the support to swing in a vertical plane, a folding supporting leg connected with the outer part of said top section, a second top section hinged at one end to one side of the first mentioned top section, said hinge connection being at right angles to the hinged connection of the first mentioned top section with the support, and a folding leg connected with the outer part of the second top section, said second top section with its leg folded thereupon being adapted to fold upon the other section, and the latter top section with its leg folded thereagainst, together with the second top section, being adapted to fold flat against one side of said support.

2. In an apparatus of the class described, a support, a bench comprising a substantially rectangular shaped top section having a hinged connection at one side to one side of the support to swing in a vertical plane, folding supporting legs connected with the outer corner portions of said top sections, a second top section hinged at one end to one side of the first mentioned top section, said hinge connection being at right angles to the hinge connection of the first mentioned top section with the support, and a folding leg connected with the outer end portion of the second top section, said second top section with its leg folded thereupon being adapted to fold upon the other top section, and the latter with its legs folded thereagainst, together with the second top section being adapted to fold flat against one side of said support.

3. The combination with a table top, and a supporting leg pivotally connected thereto, said table top having a notched part, of leg-locking means including a resilient arm secured at one end portion to the leg and having an upper part spaced from the leg,

said arm at its upper part having a reduced end portion with shoulders at opposite sides thereof, said reduced end portion being adapted to engage the notched part of the top with the shoulders engaging the under surface of the notched part.

4. The combination with a table top, and a supporting leg pivotally connected thereto, the table top having a notched part, and 10 leg-locking means including a resilient arm secured at one end portion to the leg and having an upper part spaced from the leg, said arm having a reduced upper end portion with shoulders at opposite sides thereof,

and an angularly disposed extension above 15 said shoulders, the arm being adapted to engage the notched part of the top with the reduced end portion of the arm fitting into the notch of the top, and with the shoulders and angular extension fitting against the top 20 and bottom faces of said notched part.

In testimony whereof I hereunto affix my signature in the presence of two witnesses.

PETER C. MOSSNER.
